(57) **CLAIM**

The ornamental design for a fantasy game card, as shown and described.

DESCRIPTION

FIG. 1 is a front elevation view of a fantasy game card showing my new design;

FIG. 2 is a rear elevation view;

FIG. 3 is a side view;

FIG. 4 is a top plan view; and,

FIG. 5 is an isometric view of a fantasy game card showing my new design.

The broken lines shown in FIG. 2 are for illustrative purposes only and form no part of the claimed design.
